UNITED STATES PATENT OFFICE

JOHN VALENTINE BERRY, OF JOHNSTOWN, PENNSYLVANIA, ASSIGNOR TO BETHLEHEM STEEL COMPANY, A CORPORATION OF PENNSYLVANIA

FASTENER

Application filed November 30, 1929. Serial No. 410,739.

My invention relates to fasteners and particularly to fasteners for receptacles containing emergency outfits.

In general my invention relates to fasteners for closures of receptacles which in an emergency must be accessible to anyone but which under normal conditions it is desired to be opened by only authorized persons and is particularly adaptable to first aid cabinets, fire alarm and signal boxes, and doors of first aid stations and containers for fire fighting equipment, etc.

It is therefore one of the objects of my invention to provide receptacles with fasteners which will permit the closures thereof being sealed against unauthorized persons but which can be opened by authorized persons without interfering with the seals.

Another object of my invention is to provide a fastener for a closure of a receptacle containing emergency articles with a seal and a lock, the seal being adaptable to be broken by anyone in an emergency to allow the closure to be opened and the lock being provided for the purpose of allowing authorized persons to open the closure.

The novel features will be more fully understood from the following description and claims taken with the drawings in which:

Fig. 1 shows a receptacle equipped with my improved fastener.

Fig. 2 is a cross section taken on line 2—2 of Fig. 1.

Fig. 3 is a side elevation of the fastening bar.

Referring to the drawings more in detail 10 represents one of the various type of receptacles to which my fastener is applicable.

The receptacle 10 is provided with a closure member 11 which is adapted to be retained in its closed position by my fastener 12.

The fastener 12 shown in the drawings comprises rectangular members 13 and 14 which are preferably similar in structure and 45 are provided with lateral flanges 29 and 30 and 31 and 32, respectively, for attaching these members to the receptacle. Passageways 15 and 16, are provided in the members 13 and 14, respectively, and a rectangular 50 bar member 17 which is provided at its ends

with apertures 22 and 23, respectively, to receive locking devices such as the strap of a seal 24, which may be an ordinary car seal, and the shackle of a lock 25, is slidably mounted within the passageways 15 and 16 of the members 13 and 14, respectively, to retain the closure 11 in its closed position. Elongated slots 18 and 19 are provided in the outer surface of the members 13 and 14, respectively. These slots communicate with each other and with the passageways 15 and 16, respectively so that when the passageways 15 and 16 are in registry, the pin 26, which is provided in the member 17 for the purpose of sliding this member in either direction, 65 may pass from one slot to the other. The slots 18 and 19 terminate short of the ends of the members 13 and 14 and thus provide abutments 27 and 28, respectively, for the pin 26 when the bar 17 is moved to its respective 70 extreme positions.

When an authorized person desires to gain access to the receptacle 10, he unfastens the lock 25 with the key provided therefor and removes its shackle from the aperture 23. The member 17 can now be slidably moved by the pin 19 until it leaves the member 14, whereupon the closure 11 may be opened. When an emergency arises the person desiring to gain access to the receptacle 80 10 breaks the seal 24 and removes it from the aperture 22 and slidably moves the member 17 until it leaves the member 13 whereupon the closure 11 may be opened.

When the lock 25 is removed from the aperture 23 the member 17 can be withdrawn from the member 14 but the pin 26 will engage the abutment 27 and therefore will not allow the member 17 to pass entirely out of the member 13 and when the seal 24 is removed from the aperture 22 while the lock 25 is in the aperture 23, the member 17 can be withdrawn from the member 13 but the pin 26 will engage the abutment 28 and therefore will not permit it to pass from the member 14. It will therefore be impossible for the member 17 to be misplaced while either of the locking devices is in its locking position. The member 17, however, may be easily inserted in the members 13 and 14 after 100

the pin 26 has been assembled with the member 17 when both of the locking devices are removed therefrom, thus enabling the member 17 to be inserted in the passageways 15 5 and 16 of the members 13 and 14, respectively, after these members have been attached to the closure 11 and the receptacle 10, respectively, and the pin 26 has been assembled with the member 17.

10 It will be understood from the above that I have devised a locking device which is particularly adaptable to first aid cabinets, fire alarms and signal boxes, etc., or to any place which must be accessible in emergencies and 15 which it is desired to seal against unauthorized persons, but which is always accessible to an authorized person without interfering with the sealing devices.

While I have shown my invention in but 20 one form it will be obvious to those skilled in the art that it is not so limited, but is susceptible of various other changes and modifications without departing from the spirit thereof, and I desire therefore that only such 25 limitations shall be placed thereupon as are imposed by the prior art, or as are specifically set forth in the appended claims.

Having thus described my invention what 30 I claim as new and desire to secure by Letters Patent is:

1. A fastener comprising a pair of members mounted in spaced relation to each other and having passageways therein, a connecting member slidably mounted within the passageways of said members, said connecting member being capable of slidable movement in either direction for disconnecting said members and locking means adapted to engage the connecting member to restrain said member against movement in either direction.

2. A fastener comprising a pair of substantially similar members adapted to be mounted in spaced relation to each other, said members having passageways therein, a connecting member adapted to be inserted within the passageways, each end of said connecting member having an aperture therein and means adapted to be inserted within said apertures to retain said connecting member within the 50 pair of members.

3. A fastener, comprising a pair of members having passageways therein, one of said members mounted on a relatively stationary support, the other of said members mounted on a movable support capable of movement to bring the passageways of said pair of members into and out of registry, a 55 slideable fastening member having apertures in each end thereof adapted to be mounted within the passageway of either of the aforementioned members and adapted to be moved into the passageway of the other member when the pair of members are in registry, and 60 means within the apertures of the fastening 65

member adapted to lock said member within the pair of members.

4. A fastener comprising a pair of members having passageways therein, one of said members mounted on a relatively stationary member, the other of said members mounted on a movable member and being capable of operation to bring the passageways of the pair of members into registry, a fastening member having a pin mounted thereon adapted to be slidably mounted in either of the pair of members when the passageways thereof are out of registry and means for locking said fastening member in either of the pair of members.

5. A fastener comprising a pair of members mounted in fixed relation with a receptacle and its closures, respectively, said members having passageways adapted to communicate with each other when the closure is in its closed position, a fastening member slidably mounted within the passageways of one of the members adapted to enter the passageways of the other member when the closure is in its closed position, means associated with the fastening member adapted to retain said member in locked relation with the pair of members, said means comprising an emergency seal and a lock.

6. A fastener for a receptacle comprising a pair of similar members operatively connected to the receptacle in spaced relation with each other, said members having passageways extending therethrough and slots in one face thereof, a fastening member slidably mounted within the passageways of said members, a pin operatively attached to said fastening member and adapted to slide within the slots of the pair of members, said fastening member having apertures in the ends thereof and means adapted to be inserted within said apertures to retain the fastening member within the pair of members.

7. A fastener for the closure of a receptacle comprising a pair of similar members mounted in fixed relation with the closure and the receptacle, respectively, said members having registering passageways and slots therein, a fastening member mounted in the passageways of said members, a pin operatively connected to the fastening member and slidably mounted within the slots, said fastening member having an aperture in each end thereof and locking means within the apertures for retaining said fastening member within the pair of members, said locking means comprising a seal adapted to provide means for removing said fastening member in an emergency and a lock adapted to provide means for removing the fastening member under normal conditions independently of the seal.

8. In combination with a receptacle, a fastener comprising a pair of members mounted in spaced relation on different members of

the receptacle, each of said pair of members having a passageway therein capable of registering with each other, a connecting member slidably mounted within the passageways of said members and adapted to be moved in either direction to disconnect said members and means comprising a lock for retaining said connecting member against displacement in one direction and a seal for retaining said connecting member against displacement in the opposite direction.

In testimony whereof I hereunto affix my signature.

JOHN VALENTINE BERRY.
